DEVICE FOR INCREASING STRENGTH AND LETHALITY OF EXPLOSIVES

Andrew J. Galko, Kenil, N.J., assignor to the United States of America as represented by the Secretary of the Army

Filed Jan. 29, 1964, Ser. No. 341,138
Int. Cl. F42b 1/00, 3/02

U.S. CL. 102—22

2 Claims

The invention described herein may be manufactured and used by or for the Government for governmental purposes, without the payment to me of any royalty thereon.

The invention relates to means for increasing the physical strength of explosive material while at the same time increasing the lethality or effect of the same when it is exploded.

Modern explosives can be rather roughly handled without danger of being exploded but a block or pellet of the same does not have sufficient physical strength to prevent it from being broken into pieces when subjected to rough treatment. For instance, when explosive is used as a line charge, a string of explosive pellets is projected by any suitable means, as by a rocket, across a mine field and/or across a barrier of barbed wire or the like. It is then exploded to create a path through the barrier and/or mine field. It has been found that the pellet of normal explosive material tends to be broken into pieces by the shock of the landing of the projected charge whereby to lessen the effect when exploded or to leave gaps in the path. Also, it has been found that the usual explosive is not sufficiently effective in exploding mines or clearing barbed wire. For instance, the path created by the usual explosive is too narrow whereby to require several line charges.

With the foregoing in view, it is an object of the invention to provide an improved body of explosive material which is physically stronger and which is effective when detonated to clear a wider path than conventional blocks or pellets.

A further object is to provide such an improved body of explosive by imbedding non-explosive frangible material therein.

A further object is to provide such an improved body of explosive by imbedding a body of metallic fabric therein.

A further object is to provide an improved line charge comprising a plurality of bodies of the improved pellet or the like which are connected together by a flexible member.

Other objects and advantages reside in the specific structure of invention, the structure of the several element forming the same, combinations and subcombinations of such elements, all of which will be readily apparent to those skilled in the art upon reference to the attached drawing in connection with the following specification wherein the invention is shown, described and claimed.

In the drawing:

FIG. 1 is a perspective view of one form of the invention;

FIG. 2 is a transverse sectional view taken substantially on the plane of the line 2—2 of FIG. 3;

FIG. 3 is a longitudinal sectional view taken substantially on the plane of the line 3—3 of FIG. 2; and

FIG. 4 is a fragmentary elevational view of a line charge formed by a plurality of the pellets or the like according to the invention.

Referring specifically to the drawing wherein like reference characters have been used throughout to design-

2

nate like parts, 10 designates generally a block or pellet of explosive which may be of any suitable size or shape but which in the embodiment illustrated comprises a short cylinder which is octagonal and which is formed with an axially disposed hole 11 through the same. A similarly shaped body 12 of reinforcing material is embedded in the pellet 10 concentrically thereof. The reinforcing body 12 may be of any suitable non-explosive material, and in the species illustrated comprises coarse metal fabric.

10 The above described structure not only reinforces the pellet 10 against breaking but also increases the effectiveness of each pellet when it is detonated. The force of the explosion shatters the reinforcing fabric 12 into fragments which operate like shrapnel which is effective at a much greater distance from the center of burst to explode land mines and/or demolish barbed wire than is a like pellet without the frangible reinforcement.

FIG. 4 shows a number of pellets 10 which are strung together by any suitable flexible members such as the cord 13. As many as 1800 pellets 10 may be strung together to form a line charge, the same being projected across a mine field or other barrier by a rocket or other means and then detonated by any suitable detonator, not shown, such as primer cord threaded through the holes 11 along with the cord 13. Such a charge, when detonated, can clear a path as wide as one hundred feet through wide barriers and can detonate land mines as far as thirty feet away from the center of burst. Then too, the 15 reinforcement provided by the wire mesh 12 reduces the incidence of damage to the pellets when projected as a line charge or otherwise.

While there has been shown and described what is now thought to be a preferred species of the invention, it should be understood that the same is susceptible of other forms and expressions. Consequently, the invention is not considered to be limited to the precise structure shown and described hereinabove but only as hereinafter claimed.

40 I claim:

1. An explosive line charge comprising, a plurality of octagonal plastic pellets of explosive, said pellets having central openings therein, flexible means threaded through said openings and maintaining said pellets in spaced relation, each pellet reinforced with a cylindrical body of metal fabric embedded concentrically with the central opening and symmetrical with outside contour of said explosive pellet, said metal fabric adapted to be fragmented on explosion.

2. An octagonal plastic pellet of explosive material having a central opening therein, a reinforcing cylindrical body of non-explosive metal fabric embedded in said explosive material concentrically with said central opening and symmetrical with the outside contour of said explosive body and said non-explosive metal fabric being adapted to be fragmented to form shrapnel upon explosion of said explosive material.
